16 Claims. (Cl. 309—2)

1

This invention relates to improvements in the reciprocating mechanism of crankless machines, such as are described in prior Patent No. 1,409,057, and in similar machines in which reciprocating members require to be guided in their reciprocating movements and to be supported against forces tending to displace them from their correct lines of reciprocation. Each reciprocating unit of such machines comprises one or more pistons reciprocating in a cylinder, or in coaxial cylinders and a yoke-member by which the pistons are placed in operative engagement either directly or indirectly with a rotary member of the machine. When the reciprocating unit comprises two pistons they are usually attached coaxially to the opposite ends of the yoke.

The present improvements relate to the reciprocating elements themselves, especially to the yoke member, and also to the means employed for guiding the yoke in its reciprocating movement and supporting it against forces tending to displace it from its true line of reciprocation.

An essential feature of the invention is the provision of a fixed guide-member (hereinafter called "trunk-member" or simply "trunk"), having internal and external bearing surfaces upon which the yoke, or bearing elements attached thereto, slides or slide, and having formed upon one at least of its ends a circumferential surface by which it is registered concentrically with one of the cylinders so that its bearing surfaces are parallel with the line of reciprocation of the yoke. A particular purpose of this feature of the invention is to provide trunk-members whose accurate alignment coaxially with the axes of the cylinders is brought about automatically by the form given to the parts themselves and does not require adjustment during, or after, their assembly. A further particular object is to ensure, by the accuracy of this alignment, that forces transmitted from the rotary member of the machine to the yoke, are transferred from the latter immediately to the trunk-member and are not transmitted through the pistons to the cylinder walls, which being as a rule sparingly lubricated are not well adapted to act as bearing surfaces. Means are hereinafter described for effectively lubricating the bearing surfaces of the trunk and those of the parts in sliding contact with it.

In the accompanying drawings—

Fig. 1 is a longitudinal section, in some degree diagrammatic, of a reciprocating unit and associated parts of a crankless machine having a pair of opposed coaxial cylinders, and shows a yoke

member and a trunk member therefor constructed according to the invention.

Figs. 2 and 3 are respectively a sectional side elevation and external plan view of the trunk member shown in Fig. 1.

Figs. 4 and 5 are respectively a transverse cross-section and side view, on an enlarged scale, of parts coaxing with the trunk member as shown in Figs. 1, 2 and 3.

Fig. 6 is a longitudinal section, corresponding to Fig. 1, of an alternative construction.

Fig. 7 is a cross-section of another optional construction of the trunk member and coaxing bearing member.

Figs. 8 and 9 show, in cross-section and side view respectively, another construction alternative to those shown in Figs. 1 to 7, Fig. 8 being a section on line VIII—VIII of Fig. 9.

Fig. 10 is a longitudinal section, corresponding to Figs. 1 and 6, but on a larger scale, showing further adaptations of the invention.

Figs. 11 and 12 are detailed views on a larger scale of parts shown in Fig. 10, being respectively sections on lines XI and XII of that figure.

Fig. 13 illustrates by a longitudinal section an application of the invention in which a single piston is attached flexibly to the yoke-member.

Fig. 14 is a part transverse section on the lines XIV of Fig. 13.

Fig. 15 is a transverse section, on an enlarged scale, on line XV of Figs. 13 and 16.

Fig. 16 is an external plan view, partly in section, of parts shown in Fig. 15.

As shown in Figs. 1, 2 and 3, the reciprocating unit consists essentially of the yoke 1 and pistons 2, 3, the latter being respectively attached to connecting members (hereinafter called "shanks") 4, 5, which may be integral with, or formed separately and attached to, the remainder of the yoke.

Bearing members 6, 7, 6a, 7a, of known construction make actuating engagement between the reciprocating unit and the rotating slant, or swash-plate, 8. Attached to the yoke 1, as by stud 9, is also a bearing member 10 (hereinafter called "rider") which makes sliding contact with the external surface 11 of the trunk member 12, similar contact being made with its inner surface 13 by the exterior of the yoke itself. The trunk 12 has the form of a hollow cylinder of which the outer and inner surfaces 11, 13 are accurately coaxial and from the middle portion of which an approximately semi-cylindrical portion, indicated by the dotted lines 12a, Fig. 2, has been removed in order to admit the peripheral portion of the slant 8. In the radially outward part of

the wall of the trunk 12 a longitudinal slot 14 of uniform width is formed to admit part of the rider 10 and stud 9. Both the gap 12a and the slot 14 terminate short of the ends of the trunk 12, where its cylindrical form is complete, and at these ends it is fitted firmly within the mouths of the opposed coaxial cylinders 16, 17, in which the pistons 2, 3 respectively reciprocate. The trunk 12 is thereby secured against displacement in any transverse direction. It is fixed longitudinally by being attached to one or both of the cylinders, as by screw 18, which however is to be regarded as a diagrammatic representation of other forms of fastening more suitable for the purpose, such as are described hereinafter with reference to Figs. 10, 11, 12, 13 and 14 of the drawings. It is to be observed that a trunk-member of the form above described is conveniently adapted to be machined integrally from a cylindrical tube, such as one of the drawn tubes produced by steel manufacturers.

In Figs. 4 and 5 which show on a larger scale and in greater detail portions of the yoke 1, rider 10 and trunk 12 illustrated in Figs. 1 to 3, the rider 10 is shown as being formed with integral arms 10a, 10b which make contact by portions 19a, 19b of their inner surfaces with the outer surface 11 of the trunk 12. The rider 10 has also a central inward extension 20, through which passes the stud 9 by which it is attached to the yoke 1, and which makes sliding contact with each of the faces of the slot 14, so as to prevent rotation of the yoke 1 with respect to the trunk 12 around their common axis. These bearing surfaces of the part 20, together with such portions of the outer surface of the yoke 1 as are required to make contact with the internal surface 13 of the trunk 12, may be lined with anti-friction metal, sufficient clearances being allowed in manufacture between the remainder of the mutually opposed surfaces to permit of this being done. Alternatively, in lieu of such linings of antifrictional metal, separate bearing-pads, or slippers such as those hereinafter described as being fitted to the yoke shown in Figs. 13, 15, 16, may be used. In order to adjust the necessary working clearances between the opposed bearing surfaces suitable washers or shims 21 may be inserted between the rider 10 and the yoke 1. It is to be observed that a yoke-member of the form shown in Figs. 1, 4 and 5, and in other figures of the drawings, being substantially a portion of a solid cylinder, is adapted to be machined integrally from a solid cylindrical bar with a minimum of labour and cost.

In the modified form which is shown in Fig. 6 of the trunk 12 described in connection with Figs. 1, 2 and 3, the gap, or portion actually or hypothetically removed from a complete hollow cylinder in order to form the trunk 12, is carried to the full length of the trunk at the end which is inserted into the cylinder 16, and at this end the trunk is held in contact with the cylinder on approximately one half only of the circumference, being secured thereto by the screw 18.

The modified form of the trunk shown in Fig. 6 may be adopted to facilitate assembly, and for the same purpose in certain cases the end of the trunk may have the same form and mode of fixture at both of its ends as at the end which is shown in Fig. 6 as inserted in the cylinder 16, it then having an approximately semi-cylindrical form throughout its length.

In the alternative forms of the trunk 12A and rider 10A which are shown in Fig. 7, the trunk

12, which otherwise may be similar to the trunks hereinbefore described with reference to Figs. 1 to 6, has formed on its exterior, adjacent to the slot 14, flat bearing surfaces 21a, 21b, which may preferably lie in a common plane. The rider 10A, which is attached to the yoke by stud 9, and has a part 20 fitting the slot 14 as hereinbefore described, is then formed with flat bearing surfaces as shown making sliding contact with the surfaces 21a, 21b.

As illustrated in Figs. 8 and 9 the trunk 12B, which may otherwise be as in one or other of the hereinbefore described figures, is formed without a slot but, as an alternative thereto, is provided with a longitudinal bearing surface 22 on each of its sides.

The rider, 23, which is in the form of a saddle, is formed with arms 24, 24a, 25, 25a, by which it is attached laterally to the yoke 1, as by screws 26, and makes sliding contact by its cylindrical portion 27 with the outer cylindrical surface of the trunk 12B and also by the inner surfaces of its arms 24, 24a with the bearing surfaces 22 of the trunk. These parts of the rider 23 which make contact with the trunk may be lined with anti-friction metal as indicated. Sliding contact is made between the exterior surface of the yoke 1 and the inner cylindrical surface 13 of the trunk in the same way as hereinbefore described with reference to other figures.

Figs. 10, 11 and 12 illustrate a reciprocating unit and trunk applied in accordance with the invention to a pair of opposed cylinders which respectively have, in the case of the cylinder 16 a set of oil-retention rings 30 fitting the shank 4, and in the case of the cylinder 17 a conventional type of packing 31 fitting the shank 5, the rings 30 and packing 31 being respectively contained in the cylindrical bosses 32, 33, of the flanged members 34, 35, which cover the mouths of the respective cylinders, and which may be divided diametrically in halves to facilitate assembly. The member 34 has also a cylindrical boss 36 on the side towards the yoke 1. The boss 32 fits firmly in the mouth of the cylinder 16 which is bored truly concentric with the cylinder walls, and the bosses 32 and 36 are accurately co-axial. The flange 37 of the member 35 is formed with a cylindrical recess whose edge 38 fits firmly upon the external surface of the projecting mouth of the cylinder 17, this surface being formed accurately concentric with the cylinder wall. The edge 38 and external surface of the boss 33 are also accurately co-axial.

The trunk 12C, with which the reciprocating unit makes sliding contact by means of the yoke 1 and rider 10, the latter being constructed as hereinbefore described with reference to Figs. 4, 5 and 6, except that it is attached to the yoke by two studs 9, 9, instead of one only, or by alternative means, as hereinbefore explained, is semi-cylindrical, its internal surface 13 being of the same radius as each of the bosses 33 and 36. Accordingly, when the internal surface 13 of the trunk 12C is brought closely into contact with these bosses, the guide becomes truly co-axial with the cylinders 16 and 17. This contact is shown in Fig. 11 as being effected, in the case of the boss 36 by forming at the corresponding end of the trunk 12C an axial, conically-tapered, rim 39 extending around the semi-circumference. Fitted to this conical rim is a segmental clamp 40, Figs. 10 and 11, studs 41 adapted to draw this clamp over the tapered rim 39 being studded into the end wall of the cylinder 16, these studs also,

as shown, supplementing other studs 42a in securing the flange of the member 34 to the cylinder wall. It will be seen that when the studs 41 are tightened, the end of the trunk 12 is by this means fixed both longitudinally and coaxially with respect to the cylinder 17.

At the other end of the trunk 12C different means for its location are illustrated:

Its external and internal cylindrical surfaces 11 and 13 being continued to its end, and the exterior surface of the boss 33 of the member 35 being made of the same radius as the internal surface 13 of the trunk, a short semi-cylindrical filling piece 42, having the same internal and external radii as the trunk is clamped together with the end of the trunk by the bracelet or clamp 43, this being formed in two halves and drawn together by bolts 44, as shown in Fig. 12. The length of the trunk 12C is preferably so designed in relation to the dimensions of the frame and other parts of the machine that the cylindrical end of the trunk remains clear of the face of the part 37 to a sufficient extent to prevent contact taking place between them during all movements, due to changes of temperature or other causes, to which the machine may be subjected. It will be seen that the method of fixation of this end of the trunk 12C, which has just been described, ensures its being secured coaxially with the cylinder 17 while allowing the desirable, small, longitudinal movement.

In all the applications of the invention hereinbefore described, the reciprocating member is shown as comprising two pistons attached to opposite ends of the yoke and operating in opposed coaxial cylinders. In each case, however, if a reciprocating unit with one piston only is required, any of the constructions described may be used, one of the pistons and the shank attaching it to the yoke being omitted together with the corresponding cylinder, provided that means equivalent to the inwardly projecting mouth of the omitted cylinder are used to support the trunk at that end coaxially with the cylinder at the other end.

In the construction now about to be described with reference to Figs. 13 to 16 of the drawings, the reciprocating unit and trunk are particularly designed for use with a single piston and the trunk is supported only from one end, viz. that end at which the piston is located. This piston furthermore is shown as being furnished with a piston-rod 45 by means of which it is attached to the yoke, though alternatively it may be attached to a shank forming part of the yoke, as hereinbefore described, without otherwise modifying the construction. In Fig. 13 the attachment is shown as being effected by forming a spherical end 50 on the yoke 1, and a spherical flange 51 of uniform thickness on the matching end of the rod 45, together with a cap-piece 52 fitting the back of the flange 51 and attached to the yoke 1 by screws 53 which pass loosely through holes in the flange 51. At its other end the rod 45 may be attached to the piston 3 by means of a flange as 54 into which the rod 45 is screwed and which may be either bolted rigidly to the piston as shown, or attached to it in the same way as the flange 51 to the yoke. The cylinder 17, in which the piston 3 reciprocates, is formed by means of a liner 55 of circumferentially uniform thickness fitted into the frame 56 of the machine in the usual manner, being secured longitudinally in the frame by the spring-ring 57.

The trunk 12D, which has external and inter-

nal surfaces 11 and 13 and slot 14 as hereinbefore described, is provided with a circumferential rim 58 near its end towards the cylinder and is finished between the rim 58 and its end to a cylindrical form truly coaxial with the surfaces 11 and 13 and of such diameter as to fit firmly in the mouth of the liner 55.

The face of the rim 58 remote from the cylinder is preferably spherically convex in form as shown. Over the rim 58 is fitted a ring 59 which has a corresponding concave spherical internal face and which is attached to the frame 56 of the machine by studs 60, the dimensions of the parts being so arranged that when the studs 60 are fully tightened up, the ring 59 is firmly pressed against the rim 58 and the latter against the end of the liner 55 before the ring 59 comes into contact with the frame 56. It will be seen that by this means the trunk 12D is fixed both longitudinally and coaxially with respect to the cylinder 17. In certain cases, especially in machines of small size, the trunk 12D may be formed integrally with the liner 55 as a single unit. The spring-ring 57, ring 59 and studs 60 then serve solely to secure the combined trunk and liner to the frame of the machine. Alternatively to the complete ring 59 two or more segmental clamps, similar to the clamp 40 hereinbefore described in connection with Figs. 10 and 11, may be fitted around the rim 58 to hold the trunk 12D in contact with liner 55.

The construction of the yoke 1 and its coaction with the trunk 12D are substantially the same as in the constructions hereinbefore described especially those illustrated in Figs. 4 and 5. As a further modification, however, desirable where particularly accurate and efficient guidance of the yoke is required, and in cases when it is desired to exempt the pistons when rigidly attached to the yoke from all lateral forces, the yoke is fitted with special bearing slippers 61 on both of its ends and on both of its sides (see especially Figs. 15 and 16), these slippers projecting slightly above the surface of the yoke 45 itself and alone making sliding contact with the internal surface 13 of the trunk 12D.

The faces of the slippers 61 which make contact with the surface 13 are of cylindrical form fitting the latter. The remainder of the surface 50 of each slipper is of spherical form accurately fitting spherical recesses formed in the yoke 1. The slippers are retained in these recesses by pins 62, which preferably pass loosely through holes in the slippers. Similar slippers 63 bearing 55 on the external surface 11 of the trunk 12D are fitted in the rider 10 which is formed, and attached to the yoke 1 by studs 9, 9, each as described in connection with Figs. 4 and 5, or Fig. 10, the clearances between the slippers 61, 63 and 60 the trunk 12D being regulated by suitable washers or shims 64 inserted between the enlarged portion, 65, of the stud and the rider 10, as indicated in Fig. 15.

As a further modification, in place of the extension 20 of the rider 10, which is shown in Figs. 4 and 7 as being provided for preventing rotation of the yoke 1 about its axis, a slipper-block 66 is fitted loosely on the enlarged part 65 of each of the studs, 9, 9, these blocks sliding in 70 the slot 14.

In order to lubricate effectively the surfaces 11, 13, the slippers 61, 63, and the blocks 66, 66, oil is caused to flow, as from an oil-pump, into the slot 14 from a pipe 67 and nozzle 68 mounted 75 preferably on the outer end of the trunk 12D.

Recesses 69 may be formed in the yoke 1 as shown in Figs. 13, 15, 16, to assist in the distribution of the oil to the parts to be lubricated.

Various modifications in construction, mode of operation, method and use of an invention may and do occur to others, especially after benefitting from knowledge of such a disclosure as that herein presented of the principles involved, but the invention itself is not confined to the present showing.

I claim:

1. In a mechanism comprising a cylinder, a piston working in the cylinder and a reciprocating unit of which the piston forms part, a guide comprising a trunk member having internal and external longitudinal bearing surfaces at least one of which is cylindrical adapted to make sliding contact with corresponding surfaces provided on said reciprocating unit.

2. In a mechanism comprising a cylinder, a piston working in the cylinder and a reciprocating unit of which the piston forms part, a guide comprising a trunk-member fixed coaxially with respect to said cylinder and having internal and external bearing surfaces at least one of which is cylindrical adapted to make sliding contact with corresponding surfaces provided on members forming parts of said reciprocating unit.

3. In a mechanism comprising a cylinder, a piston working in the cylinder and a reciprocating unit of which the piston forms part, a guide comprising a trunk-member fixed coaxially with respect to said cylinder and having formed upon it an internal cylindrical bearing surface, an external cylindrical bearing surface and at least one longitudinal bearing surface transverse to said cylindrical surfaces, all said bearing surfaces being adapted to make sliding contact with corresponding surfaces provided on members forming parts of said reciprocating unit.

4. In a mechanism comprising a cylinder, a piston working in said cylinder and a reciprocating unit of which the piston forms part, a guide comprising a trunk-member having formed upon it internal, external and substantially radial bearing-surfaces, members forming parts of the reciprocating unit and severally provided with bearing surfaces adapted to make sliding contact with said internal, external and radial bearing surfaces and means for fixing said trunk-member coaxially with respect to said cylinder.

5. In a mechanism according to claim 1, the trunk member having formed on one of its ends a circumferential surface by means of which it is registered coaxially with the cylinder so that its longitudinal bearing surfaces are parallel with the line of reciprocation of the reciprocating unit.

6. In a mechanism comprising a cylinder, a piston working in the cylinder and a reciprocating unit of which the piston forms a part, a guide comprising a trunk-member having formed on one of its ends a cylindrical surface by means of which it is registered coaxially with the cylinder and means for fixing said trunk-member relatively to the cylinder in the longitudinal direction.

7. In a mechanism according to claim 6, in which the means for fixing the trunk-member relatively to the cylinder in the longitudinal direction comprises a spherical surface transverse to said cylindrical surface.

8. In a mechanism comprising a cylinder, a piston working in the cylinder and a reciprocating unit of which the piston forms a part, a guide

comprising a trunk-member of which the part by which sliding contact is made with the reciprocating unit is substantially a portion of a hollow cylinder and the internal and external longitudinal bearing surfaces are portions of circular cylinders coaxial with one another and with the cylinder in which the piston works.

9. In a mechanism according to claim 4, a part of the trunk-member by which sliding contact is made with the reciprocating unit being substantially a portion of a hollow cylinder, with concentric external and internal longitudinal bearing surfaces, and the radial bearing surfaces, being the bounding surfaces of a slot formed longitudinally in the wall of said hollow cylinder.

10. In a mechanism comprising a pair of coaxial cylinders, pistons working in the cylinders and a reciprocating unit of which the pistons are parts, a guide comprising a trunk-member extending between the cylinders and having internal and external bearing surfaces adapted to make sliding contact with corresponding surfaces on said reciprocating unit, a circumferential cylindrical surface on each of its ends by means of which it is registered coaxially with the cylinder at that end, and means by which the said trunk-member is fixed relatively to one at least of said cylinders in the longitudinal direction.

11. In a mechanism comprising a cylinder, a piston working in the cylinder and a reciprocating unit of which the piston forms a part, a guide comprising a trunk-member, said trunk-member being substantially a portion of a hollow cylinder adapted to be formed integrally from a hollow tube.

12. In a mechanism comprising a cylinder, a piston working in the cylinder and a reciprocating unit of which the piston forms a part, a guide comprising a trunk-member, said reciprocating unit comprising a yoke-member having a bearing surface adapted to make sliding contact with the internal longitudinal bearing surface of the trunk-member and a rider having a bearing surface adapted to make sliding contact with the external longitudinal surface of the trunk-member.

13. In a mechanism comprising a cylinder, a piston working in the cylinder and a reciprocating unit of which the piston forms a part, a guide comprising a trunk-member having formed upon it internal, external, longitudinal substantially cylindrical bearing surfaces and substantially radial bearing surfaces, said reciprocating unit comprising a yoke-member having a bearing surface adapted to make sliding contact with the internal longitudinal bearing surface of the trunk-member, a rider-member having a bearing surface adapted to make sliding contact with the external longitudinal surface of the trunk-member and a member adapted to make sliding contact with the substantially radial surface or surfaces of the trunk-member.

14. In a mechanism comprising a cylinder, a piston working in the cylinder and a reciprocating unit of which the piston forms a part, a guide comprising a trunk-member having an internal substantially cylindrical longitudinal bearing surface, a yoke-member forming part of the reciprocating unit and having substantially the form of a portion of a solid cylinder adapted to make sliding contact by its periphery with said cylindrical surface of the trunk-member and to be formed integrally from a cylindrical bar.

15. In a mechanism comprising a pair of co-

axial cylinders, a hollow trunk member interposed between said cylinders, a piston in each of the cylinders, a yoke interconnecting the pistons, said trunk member having circumferential end-portions fitting into the cylinders and affixed to at least one of the cylinders and having an inner cylindrical longitudinal bearing surface coaxial with the cylinders, and a cylindrical surface on the yoke in slidable engagement with said bearing surface.

16. In a mechanism comprising a pair of coaxial cylinders, a hollow trunk member interposed between said cylinders, a yoke interconnecting the pistons, said trunk member having circumferential end-portions fitting into the cylinders and affixed to at least one of the cylinders and having an inner cylindrical longitudinal bearing surface coaxial with the cylinders, a cylindrical surface on the yoke in slidable engagement with said bearing surface.

ment with said bearing surface, and means for preventing relative rotation between the yoke and the trunk member.

ANTHONY GEORGE MALDON MICHELL.
